(57) CLAIM

The ornamental design for a flower shaped memo holder, as shown and described.

DESCRIPTION

FIG. 1 is a perspective view of the flower shaped memo holder of the present invention;

FIG. 2 is a front view of the invention shown in FIG. 1;

FIG. 3 is a back view thereof;

FIG. 4 is a top plan view thereof, taken from the perspective of one looking down upon the flower shaped memo holder shown in FIG. 1;

FIG. 5 is a bottom plan view thereof taken from the perspective of one looking up upon the flower shaped memo holder shown in FIG. 1;

FIG. 6 is a left side view thereof; and,

FIG. 7 is a right side view thereof.
